(57) **CLAIM**

The ornamental design for a candle with wood chips, as shown and described.

DESCRIPTION

FIG. 1 is a front perspective view of a candle with wood chips according to our new design.

FIG. 2 is a top plan view of the candle with wood chips of FIG. 1; and,

FIG. 3 is an enlarged partial front perspective view of the candle with wood chips of FIG. 1.

The dash-dash broken lines in the drawings depict environment and portions of the article that form no part of the claimed design.
